(57) **CLAIM**

The ornamental design for a solar-charging mounting bracket for video doorbell, as shown and described.

DESCRIPTION

FIG. 1 is a front perspective view of a preferred embodiment of the solar-charging mounting bracket for video doorbell according to the present design;

FIG. 2 is a front elevational view of the solar-charging mounting bracket for video doorbell of FIG. 1;

FIG. 3 is a rear elevational view of the solar-charging mounting bracket for video doorbell of FIG. 1;

FIG. 4 is a right-side elevational view of the solar-charging mounting bracket for video doorbell of FIG. 1;

FIG. 5 is a left-side elevational view of the solar-charging mounting bracket for video doorbell of FIG. 1;

FIG. 6 is a top plan view of the solar-charging mounting bracket for video doorbell of FIG. 1; and,

FIG. 7 is a bottom plan view of the solar-charging mounting bracket for video doorbell of FIG. 1.

In the drawings, the broken lines depict portions of the article that form no part of the claimed design.
